UNITED STATES PATENT OFFICE.

MICHAEL W. MURRAY, OF LONGMEADOW, MASSACHUSETTS.

TOOL-HOLDER.

No. 906,263.

Specification of Letters Patent.

Patented Dec. 8, 1908.

Application filed May 14, 1908. Serial No. 432,862.

To all whom it may concern:

Be it known that I, MICHAEL W. MURRAY, a citizen of the United States of America, residing at Longmeadow, in the county of 5 Hampden and State of Massachusetts, have invented new and useful Improvements in Tool-Holders, of which the following is a specification.

This invention relates to improvements in 10 tool-grinding or sharpening devices, and has special reference to the grinding of plane irons, chisels, and gouges so that the same angle will always be maintained during the grinding process.

15 The invention is also designed so the operator may readily inspect the edge of the tool during the process of grinding the same.

It also has for its object to so construct the device that it may be readily brought into 20 use, and folded away from the revolving stone when not in use.

In the drawings forming part of this application,—Figure 1 is a side elevation on line 1—1 of Fig. 2 showing the device partly in 25 section and a tool in place during the process of grinding, and in dotted lines the clamping frame in a lifted position while inspecting the tool. Fig. 2 is an end elevation of Fig. 1 looking from the left-hand side of the figure.

30 Fig. 3 is a plan view of Fig. 1. Fig. 4 is a perspective view of the tool-holding portion of the device showing the same in use when grinding a gouge. Fig. 5 is a transverse sectional view on the line 5—5 of Fig. 4. Fig. 6

35 is a transverse sectional view on the line 6—6 of Fig. 3 showing the construction of the clamp for holding a plane iron or chisel. Fig. 7 is a transverse sectional view on line 7—7 of Fig. 5 showing the construction of 40 the clamp that is used for holding a gouge while being ground or sharpened.

Referring to the drawings, *a* designates an emery wheel or grindstone mounted on the shaft *a*¹ in any approved manner.

45 *b* designates a metal standard secured to the framework in which the stone is mounted, the same being provided with a slot *c* therein. The standard is adapted to adjustably hold an angular bracket-arm *d* which is secured to the standard *b* by means of the bolt *e*.

Slidably mounted on the horizontal arm *f* of the bracket-arm *d* is a hinge member *g* that is adjustably secured to the horizontally disposed arm *f* by means of the set-screw *h*.

55 This member is provided with the ears *i* in which is pivotally mounted the vertically ar-

ranged bolt *j* which is provided with a nut *k* at its upper end. The bolt *j* is further provided with a turned or finished portion *m* for pivotally securing the sleeve *n* to the hinge 60 member *g*. The hinge member *g* is pivotally connected to the bolt *j* by means of the pin *j*¹. Slidably mounted in this sleeve is a rod or tube *o* which is prevented from rotation by means of the bolt *p* engaging the longitudinal 65 slots *q* which are diametrically cut in the sleeve member, as shown. The nut *p*¹ locks the tube *o* to the sleeve *n*. The forward end of the rod or tube *o* is provided with a thumb-screw *r* that is adapted to lock the yoke-shaped handle member *s* against rotation 70 when sharpening a plane iron or chisel, but will at the same time permit said member to rotate when the thumb-nut is loosened. The handle-member *s* is provided with the 75 transverse slot *t* as shown in Fig. 5, for allowing the same to be rotated transversely. The left-hand end of the handle member *s* is provided with hand openings *u* for enabling the user to operate the device as will be described. Pivots secured to the arms *w* of the handle member *s* is a rectangular tool-holding frame *v* that is connected to the arms *w* of the handle member *s* by means of the pivot screws *x*.

85 *y* designates an arc-shaped slot in the clamping member *z*¹ of the tool-holding frame *v* and passing through the slot is the thumb-nut *2* which screws into the arms *z* of the clamping-frame *v* whereby the member *z*¹ is 90 adjustably secured to the arms *z* of the frame *v* and the chisel or plane iron can then be ground at any desired angle. The inner ends of the arms *z* of the frame *v* are pivotally mounted on the screws *x* which pass through 95 the inner ends of the arms *z* and into the clamping member *z*¹ proper of the frame *v*. This construction therefore permits the member *z*¹ to be moved independently of the arms *z*, and with the arms *z* when the thumb-nut *2* is tightened after the tool is inserted 100 and properly clamped. In order to clamp a tool for sharpening it in the frame *v*, the clamping member *z*¹ is made channel-shape in cross section, as shown in Figs. 6 and 7, on 105 the underside thereof. The clamping member *z*¹ is provided with a rectangular member 4 through which the chisel or plane iron 5 is inserted.

110 *6* designates the thumb-nut that is threaded onto the stem member *7* that is integral with the upper portion of the frame 4 where-

by this frame may be drawn upward into the channel portion of the member z^1 , and the chisel or plane iron clamped between the upper edge of the member z^1 and the lower member or bar 4^1 of the rectangular member 4, as clearly shown in Figs. 1 and 6.

Fig. 7 shows a modification in which a gouge is shown clamped in the frame element z^1 by means of the holder 9 which has a curved bottom bar 9^1 corresponding to the curvature of the gouge.

Referring now to the operation of the grinding device: After a chisel or plane iron is clamped as described, and the angle 15 properly adjusted by means of the thumb-nut 2, the operator tightens the thumb-nut r so as to prevent any lateral rotation of the handle-member s ; then by grasping the handle openings u , suitable pressure may be placed on 20 the tool while being ground or sharpened. The pivots x which secure the arms z to the handle-member s permit the operator to lift the chisel or plane iron from the stone or emery-wheel so that the edge of the same 25 may be inspected during the sharpening process. The rod o can be freely moved longitudinally in the sleeve n for permitting the tool to be moved towards and from the stone. The lips v^1 of the frame v engage the upper 30 edge of the arms w for preventing the frame v dropping down too far. In practice, the rod o is clamped to the sleeve n and the tool ground by bearing down on the handles.

When it is desired to grind a gouge, the 35 rectangular clamping frame 4 is removed and the clamping frame shown in Fig. 7 is substituted therefor, and the gouge, which is designated at 8, is suitably clamped therein by means of the thumb-nut 6. The operator 40 then loosens the thumb-nut r which permits the hand-frame s to rotate axially of the rod o thus allowing the gouge to be ground on a curvature, and at the same time permit the frame s to have longitudinal movement in the 45 sleeve n , if required, by loosening the nut p^1 . The gouge can be readily inspected during the grinding process by simply lifting the frame member v in the manner already described.

50 When the device is not in use, it can be readily folded into a vertical position by simply rotating the rod o on the bolt j about the bearing portion m , and the pivot j^1 will then permit the rod o to be folded into a vertical 55 position against the bracket d as readily understood.

What I claim, is:—

1. In a grinding device of the class described, an upright member, a bracket secured thereto, a sleeve pivotally secured to the bracket, a rod longitudinally movable within the sleeve, a tool-clamping member, and means for securing the tool-clamping member to the rod, said means permitting 65 the tool to have a lateral rotary movement

with relation thereto, and means for adjusting the tool at different angles.

2. In combination with a tool-holding member, means for adjusting the member at different angles, a handle-member, means for pivotally securing the tool-holding member to the handle member, and means for pivotally securing the handle-member to a supporting element. 70

3. In combination, a tool-clamping member, a rod, means for slidably connecting the rod to a standard, a handle member rotatably connected to the rod, said tool-clamping member being pivotally connected to the handle member, and means for adjusting the 75 plane of the tool with relation to the handle member.

4. In combination, a standard, a tool-clamping member, a rod, means for slidably connecting the rod to a standard, a handle member rotatably connected to the rod, said tool-clamping member being pivotally connected to the handle member, and means for adjusting the plane of the tool with relation to the handle member. 80

5. In combination, a tool-clamping member, a rod, means for slidably connecting the rod to a standard, a handle member rotatably connected to the rod, said tool-clamping member being pivotally connected to the handle-member, means for adjusting the plane of the tool with relation to the handle-member, means for permitting the rod to be moved in either a 95 vertical or horizontal plane.

6. In combination, a handle member, a 100

tool-clamping member pivotally mounted therein, a rod for supporting the same, means for adjustably retaining the tool-clamping member in different angular positions of adjustment, and means for permitting the handle member to move in a direction transverse to the axis of the rod. 110

7. A tool-grinding device having in combination, a rod, means for permitting the same to move in horizontal and vertical 115 planes, a handle member having means for rotatably connecting said member and rod, a tool-holding frame pivotally connected to the handle member, a tool-clamp and means for adjustably securing the tool-clamp to the 120 tool-holding frame, said frame being provided with stop means to engage the handle member, as described.

8. A tool-grinding device having in combination a handle member, a tool-holding frame pivoted thereto and having stop members engaging the handle member, thumb-nuts 2 for varying the angle of adjustment with the handle-member, a standard, a rod 125 slidably and pivotally secured thereto, and 130

means for securing the handle member to the rod, justably and pivotally connected to the rod, as described.

9. A tool-grinding device having in combination, a standard, a bracket secured there-
to, a rod connected to the bracket by a uni-
versal joint construction, a handle member
secured to the rod, a tool-holding frame ad-
